United States Patent Office.

WARREN LYON, OF NEW YORK, N. Y.

Letters Patent No. 65,248, dated May 28, 1867.

IMPROVED MACHINE FOR CUTTING STUBS.

The Schedule referred to in these Letters Patent and making part of the same.

TO ALL WHOM IT MAY CONCERN:

Be it known that I, WARREN LYON, of the city, county, and State of New York, have invented a new and improved Machine for Cutting Stubs; and I do hereby declare that the following is a full, clear, and exact description thereof, which will enable others skilled in the art to make and use the same, reference being had to the accompanying drawings, forming part of this specification.

This invention relates to a new and improved machine for cutting rods into small pieces for connecting the parts of iron railings together. These pieces are technically termed "stubs," and they are fitted in holes made in the ends of the bars, and secured therein by "setting" or striking the metal of the bars so that it will firmly clinch or hold the rods or "stubs," the protruding ends or portions of the "stubs" passing through holes in the rails or adjoining bars, and riveted at their ends at the outer sides of the latter-named rails or bars, so as to form a firm connection.

The object of the invention is to obtain a simple, economical, and portable device for the purpose specified, and one which may be operated with the greatest facility. In the accompanying sheet of drawings—

Figure 1 is a side view of my invention.

Figure 2, an end view of the same.

Figure 3, a horizontal section of the same, taken in the line *xx*, fig. 1.

Similar letters of reference indicate like parts.

A represents an upright plate of cast iron, and cast with a base, *B*, and *C* is a pinion, which is fitted on a fixed axis, *a*, at the upper part of *A*, and is provided with a handle, *D*. To one side of the plate *A* there is secured by a pivot, *b*, another plate, *E*, which is allowed to work or turn freely on the pivot *b*. On the upper end of the plate *E* there is a segment-rack, *F*, which is a portion of a circle of which the pivot *b* is the centre, and the pinion *C* gears into this rack. (See figs. 1 and 2.) To the inner surfaces of the plates *A* *E* there are firmly secured steel plates *c* *d*, which have circular holes *c*^x made through them to allow the rod to be passed through them, corresponding holes *c* being made in the plates *A* *E*, (see fig. 3,) the holes *c* being in line with the holes *c*^x in the steel plates *c* *d* when the plate *E* is in an upright position, and a pin, *f*, which projects from the inner side of the plate *E*, is in contact with a projection, *g*, on the plate *A*. The plates *c* *d* serve as cutters, and cut the rod, when the same is passed through the holes in the plates *A* *E* and *c* *d*, and the plate *E* moved by turning the pinion *C* through the medium of the handle or lever *D*. By this rack, pinion, and handle or lever, a considerable purchase or leverage power is obtained, and the rod cut with a very slight expenditure of power. The rod is cut into pieces or "stubs" of a greater or less uniform length, by means of an adjustable gauge composed of an arm, *F*, fitted on a pivot, *h*, which projects from a pendent plate, *i*, of a tube, *j*, the latter being fitted on a rod, *k*, which projects horizontally from the plate *A*, and is secured on said rod *k* by a set-screw, *l*. The upper part of the arm *F*^x is kept in contact with a pin, *m*, which projects from the plate *i*, by means of a spring, *n*, and the lower part of the arm *F*^x, when the gauge is in use, is in line with the holes *c*^x in the steel plates *c* *d*, and serves as a stop when the rod is passed through the holes in the plates *A* *E* *c* *d*, the arm being adjusted nearer to or farther from plate *A*, according to the length required for the "stubs," by adjusting the tube *j* on the rod *k*. The "stubs" are forced out from the plates as they are cut, by shoving or feeding the rod through the same, the arm *F* yielding to allow the "stubs" to pass out, the spring *n* throwing the arm back to its proper position as soon as each "stub" drops from plate *A*. When the gauge is not required it may be turned to one side of the holes in the plates by turning the tube *j* on its rod *k*. This device may be screwed or bolted to a bench or fixture, and will monopolize but very little room.

Having thus described my invention, I claim as new, and desire to secure by Letters Patent—

The operating of the pivoted plate *E*, through the medium of the segment-rack *F* and pinion *C*, when said plate *E* has a cutting plate, *c*, attached, and is used in connection with a similar cutting plate, *d*, on a fixed standard or plate, *A*, to which the plate *E* is pivoted, all arranged substantially as and for the purpose specified.

The combination of devices composing the gauge, arranged substantially as and for the purpose set forth.

WARREN LYON.
